UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

SUBMARINE SIGNALING.

1,811,157.

Specification of Letters Patent. Patented July 29, 1912.

Application filed March 18, 1912. Serial No. 222,000.

To all whom it may concern:

Be it known that I, REGINALD A. FESSENDEN, of Brookline, in the county of Norfolk and State of Massachusetts, a citizen of the 5 United States, have invented new and useful improvements in Submarine Signaling, of which the following is the specification.

My invention relates to signaling in fluid media and more especially to submarine signaling.

10 My invention has for its object increased efficiency in signaling in fluid media and more especially in submarine signaling and still more especially it relates to a secret 15 system of submarine signaling, whereby friendly submarines can communicate with each other and whereby they can send out secret recognition signals so that friendly submarine chasing vessels may recognize 20 them and not attempt to destroy them under the impression that they are enemy submarine vessels.

The invention is likewise applicable to aeroplane work, especially to aeroplane work 25 at night time.

The inclosed figure, forming a part of this specification, shows, partly diagrammatically, suitable means for carrying out my invention. Here 11 is the stern of a submarine; 12 the propeller; 13 the propeller shaft; 14 the motor driving the propeller; 15 a remote control main circuit switch, which on being closed starts the motor and on being opened cuts the current off from 25 the motor. 16 are the storage batteries for driving the motor; 18 is a rotating make and break mechanism, having adjustable contacts 17, 17, 17 suitably spaced about its periphery; 19 is a brush for making contact with 30 the contacts 17, 17, 17 as the contact maker 18 revolves; and 20 is a local battery for operating the remote control main circuit switch 15, and 21 is a telegraph key.

The operation of the device is as follows: 35 The submarine is assumed to be traveling submerged. On reaching the area where it is desired to emit recognition signals the rotating make and break mechanism 18 is set in motion so as to revolve at any suitable 40 speed; for example, once per minute and key 21 is closed. This being done, every time the contacts 17, 17, 17 come in contact with the brush 19, the motor circuit is opened

for an instant by the remote control main circuit switch and the motor armature ceases 55 for an instant to exert a torque on the propeller.

The motor will, of course, not stop entirely as it will continue to revolve, though with rapidly diminishing speed, owing to 60 the inertia of the armature and shaft, but applicant has found by actual trial that the cutting off of the current from the motor even for an instant makes a pronounced and marked change in the propeller noises and 65 hull vibrations as heard through the water, and consequently these brief interruptions of the motor circuit can be used for signaling to a vessel equipped with apparatus for listening to the propeller sounds and hull 70 vibrations through the water.

The contacts 17, 17, 17, being adjustable, may be varied from day to day in accordance with a prearranged schedule so that on one day the recognition signal will be 75 a Morse "O", on another day a Morse "I" and on still another day a Morse "R", etc., and a trawler or destroyer which it is desired should recognize the recognition signal of the submarine may be furnished in advance with the recognition signals for an 80 entire month if thought desirable.

Should the submarine wish to telegraph to trawlers or destroyers or to another submarine, it may do so by interrupting the 85 motor circuit by the telegraph key 21 in the same way as in ordinary telegraphing.

This method possesses a number of important advantages:

A. The recognition sounds are produced 90 by varying the detection sounds so that any trawler or destroyer which detects a submarine by hearing its propeller noises and hull vibrations must hear the recognition signal and consequently cannot possibly 95 make the mistake of bombing a friendly submarine. This avoids the danger that if the recognition signal were produced by a separate and special means, for example a sharply tuned note or an ultra-audible vibration, the separate and special signal might not be heard and the submarine might 100 be bombed by mistake.

B. The recognition signal of the submarine cannot be heard by unfriendly vessels under any circumstances where the sub- 105

marine would not be heard in any case, because if the unfriendly vessel does not hear the propeller sounds and hull vibrations of the submarine it will not hear the 5 recognition signal, and vice versa.

C. The type of recognition signal is one which if heard by an unfriendly vessel would naturally be supposed to be due to an 10 accidental stoppage of the motor, and the signal is rapidly variable.

In place of interrupting the motor current many other obvious devices may be used; for example, the clutch connecting the motor and the propeller shaft may be caused to 15 slip or the making of the contacts may cause the motor speed to increase instead of to decrease.

What I claim is:—

1. The method of signaling in a fluid medium which consists in varying by control in a predetermined manner the noises produced by the motion of a vessel through the fluid medium, whereby intelligible predetermined signals may be given to a distant observer.

2. The method of signaling in a fluid medium which consists in varying momentarily the speed of the propelling mechanism of a vessel traversing said fluid medium according to a predetermined code whereby intelligible signals may be given to a distant observer.

REGINALD A. FESSEMENDEN.
